UNITED STATES PATENT OFFICE

2,665,639

PUMP STRUCTURE

Ernest J. Svenson, Rockford, Ill., assignor to Odin Corporation, Chicago, Ill., a corporation of Illinois

Original application May 3, 1939, Serial No. 271,444. Divided and this application November 7, 1946, Serial No. 708,340

7 Claims. (Cl. 103—42)

1

This invention relates to pump structures, and more particularly to pump structures of the reversible type adapted for propelling fluid to and receiving fluid from an actuated device, and wherein the fluid requirements of the actuated device are different in its opposite directions of travel.

It is an object of the invention to provide a pump structure of the foregoing type, of improved construction and improved operating characteristics.

More specifically stated, it is an object of the present invention to provide an improved pump structure, such as a rotary gear pump or the like, which incorporates improved means for compensating the pump delivery, both to make up fluid deficiency and to dissipate fluid excess, as for example in installations wherein a differential exists in the volumetric delivery of fluid to and from the pump in normal operation.

A still further object of the invention is to provide an improved reversible gear pump, and compensating means therefor.

This application is a division of my prior copending application, Serial No. 271,444, filed May 3, 1939, and entitled "Hydraulic Actuator Mechanism," now abandoned in favor of my application, Serial No. 708,339, filed November 7, 1946, as a continuation-in-part of the earlier application, and of which the present application also constitutes a division. The present application concerns particularly the pump structure disclosed in said prior cases.

Various other objects, advantages and features of the invention other than those hereinbefore specifically referred to, will appear from the following specification when taken in connection with the accompanying drawings wherein certain preferred embodiments of the invention are illustrated.

In the drawings, wherein like reference numerals refer to like parts throughout:

Fig. 1 is a general assembly view, somewhat diagrammatic in form, of a printing press shiftable roller installation incorporating pump structures constructed in accordance with and embodying the principles of the invention;

Fig. 2 is a view on an enlarged scale of the hydraulic actuator structures, and associated parts, as embodied in the structure shown in Fig. 1;

Fig. 3 is a detail sectional view of the pump structure and associated parts, in the installation of Figs. 1 and 2, taken as indicated by the line 3—3 of Fig. 2;

2

Fig. 4 is a sectional view through the pump and associated actuator cylinder, taken on the line 4—4 of Fig. 3;

Figs. 5, 6 and 7 are sectional views of a modified form of pump structure, Figs. 6 and 7 being taken on the lines 6—6 and 7—7, respectively, of Fig. 5;

Fig. 8 illustrates a further representative installation incorporating pump structures constructed in accordance with the invention, the installation shown being one for effecting the hydraulic shifting of valves; and

Fig. 9 and 10 are sectional detail views, on an enlarged scale, of the valve actuator structures, and associated parts, as shown in Fig. 8, and taken on the lines 9—9 and 10—10, respectively, thereof.

In many installations which are adapted for pump actuation, the requirements of the system are such that a differential exists between the volume of fluid to be propelled from and delivered to the pump during its actuation. For example, in instances wherein a gear pump is interconnected with a reciprocable hydraulic actuator in a closed circuit, if the actuator has a piston rod projecting from only one end thereof, as is frequently the case, a differential will exist between the volume of fluid which must be delivered to the actuator to effect the propulsion of the actuator piston, and the volume of fluid which is returned from the actuator to the pump, from the return side of the piston. If the pump is reversible, and thus arranged to propel the actuator piston in opposite directions of travel, an excess of fluid will be returned to the inlet side of the pump during actuation of the actuator piston in one direction of travel, whereas there will be a deficiency in the amount of fluid returned to the inlet side of the pump when the actuator piston is propelled in its opposite direction of travel.

In accordance with the present invention an improved pump structure is provided, having improved features and characteristics, and including improved means for compensating the fluid delivery of the pump in accordance with the foregoing requirements.

In Figs. 1—7 of the drawings, an embodiment of the invention is illustrated wherein pump propelled hydraulic actuator mechanisms are utilized for shifting printing press rollers, whereas in Figs. 8—10 the pump structure of the invention is shown as applied to the shifting of valves or the like. It is to be understood, however, that the pump of the invention, and the various char-

acteristics thereof, are adapted for use in a wide variety of installations, including installations for effecting the hydraulic propulsion of various machine parts.

Referring more particularly to the drawings, and first to the structures illustrated in Figs. 1-4, in Figs. 1 and 2 there is illustrated a printing press or paper handling machine incorporating three units 12, 14 and 16, each of which is provided with a hydraulic actuator structure for shifting the paper handling rolls.

As shown in Fig. 2, each unit includes a reversible electric motor 18 adapted to drive a gear pump 20 mounted within a liquid reservoir 22. As will presently appear, the intake and exhaust passages of the pump are hydraulically connected to a reversible hydraulic actuator 24 which through suitable mechanical linkage shifts the roller or blanket cylinder 26 upwardly out of engagement with the pressure cylinder 30, or downwardly into engagement with said pressure cylinder and the associated paper supporting web 31, as the occasion may require, to effect the printing operation.

Referring more specifically to the hydraulic actuator structure shown, it will be seen that a housing 95 integral with a support plate 93 mounted on the frame bracket 32 supports the actuator cylinder 36, Fig. 3, cast integrally with the outer housing member 92 of the pump 20. A piston 38, Fig. 4, carried by a piston rod 40 operates within the cylinder, there being end plates or covers 42 with the usual sealing means or gasket 44 and piston rod packing means 46, for preventing fluid leakage from the cylinder along the piston rod.

The piston rod 40 carries at its outer or upper end a yoke member 48 mechanically interconnected with the linkage previously mentioned, for effecting the desired shifting operations.

Motor 18, which may be of any suitable reversible type, is connected to the pump 20 by any suitable or conventional coupling 86, Figs. 2 and 3, interposed between and secured to the motor shaft 98 and the actuating shaft 90 of the pump 20. The pump 20 comprises a housing member 92 formed integrally with the cylinder 36, and a cover plate 94, the pump 20 projecting into and being mounted upon the housing 95 forming the oil reservoir 22. The oil reservoir housing is formed integrally with the support plate 96 for the motor 18.

The pump drive shaft 90 is journaled in bushings 98 and is provided with a suitable liquid seal 100 preventing leakage of the liquid along the shaft. A drive gear 102 is cut integrally with the shaft 90 and meshes with a companion pump gear 104 secured to a rotatable sleeve 106 journaled on a normally stationary but adjustable pin or stud shaft 108 held in position by its shoulder 110 and a cap screw 112. The pump gear 104 is provided with a set of angularly spaced radial passages 114 communicating with similar radial passages 116 in the sleeve 106, the passages 116 being adapted to communicate in sequence with slots or chambers 118 and 119 formed in the shaft 108. Liquid trapped between the teeth of the gears at the meshing position is relieved by the passages 114, 116 and the chambers 118 and 119, the chamber 118 being operative when it is on the outlet or discharge side of the pump as the pump is operating in one direction, and the chamber 119 being operative when it is on the discharge side as the pump is operating in the reverse direction. The

chambers relieve the liquid trapped between the teeth of the gears, preventing crushing thereof by allowing it to be relieved back into the exhaust chamber. If desired, the sides of the teeth of

5 the gear 104 may be radially grooved to provide additional relief passages as will be more particularly pointed out hereinafter in reference to the embodiment of the invention shown in Figs. 5, 6 and 7. Also, shaft 108 may be adjusted rotatably to permit the return of liquid from the high to the low pressure side of the pump through the chambers 118 or 119 in regulatable amounts as determined by the adjustment of the shaft. See, for example, Svenson Patents Nos. 1,912,737 and 1,912,738, dated June 6, 1933.

The chamber containing the pump gears 102 and 104 is connected to the actuator cylinder 36 by liquid supplying and discharging ports 120 and 122, the port 120 constituting the inlet and the 20 port 122 the outlet when the pump gears are driven in one direction, and the port 120 constituting the inlet and the port 122 the outlet when the pump gears are driven in the opposite direction. The port 120 extends into communication with the cylinder 36 above the piston as seen in Fig. 4, and the port 122 extends into communication with the cylinder below the piston.

It will be apparent that in a closed hydraulic system or circuit, such as disclosed, wherein the 25 piston rod 40 occupies a portion of the cylinder on one side only of the piston, there exists a difference in the volume of liquid displaced on opposite sides of the piston per unit of piston movement. In order to compensate for this difference in volume there are provided two compensating 30 channels or passages 124 and 126 extending through the pump housing member 92 radially with respect to the pump gears and from the pumping chamber into communication with the reservoir 22. When the pump gear 102 is driven 35 in a counterclockwise direction as seen in Fig. 4, liquid is supplied to the pump chamber through the port 120 from the chamber 128 above the piston 38 and forced, under pressure, through the port 122 into the chamber 130 below the piston 38. As the piston 38 moves upwardly or outwardly, less liquid is displaced per unit of movement than is required to fill the space created below the piston by the same unit movement. Therefore, it may be stated that less liquid is available to the inlet port 120 of the 40 pump from the chamber 128 above the piston than must be supplied through the outlet port 122 of the pump to the chamber 130 to move the piston 38 upwardly. As the piston 38 moves upwardly, a slight vacuum is thereby created in the inlet port 120 due to this difference in the volume of the displaced liquid on opposite sides of the piston and accordingly when each partially filled 45 space between an adjacent pair of teeth of the pump gears 104 and 102 registers with the increasing compensating ports or passages 124 and 126, additional liquid sufficient to fill these spaces is supplied from the reservoir through these ports 124 and 126.

When the pump drive gear 102 is rotated in the clockwise direction, as seen in Fig. 4, more liquid is available to the inlet port 122 of the 50 pump per unit of movement of the piston than can be accommodated by the chamber 128 above the piston. This surplus liquid creates a slight pressure in the inlet port 122 and is relieved by liquid passage through the ports 124 and 126 into the reservoir 22 as the spaces between ad-

jacent teeth on the pump gears register with the ports 124, 126.

It will be evident from the description of the form of the invention illustrated in Figs. 1 to 4, that applicant has provided a very simple and efficient pump structure for propelling a machine part, a printing press cylinder in the specific embodiment illustrated, and that by reversal of the driving motor, the direction of movement of such a machine part may be readily controlled without the use of any additional valve mechanisms.

For installations wherein there is a still greater difference in the volume of liquid displaced on opposite sides of a piston per unit of movement, the invention provides the modification illustrated in Figs. 5 to 7. In this form of the invention the pump gear 104' is provided with two axially spaced sets of radial passages 114' leading inwardly from the spaces between the gear teeth, and is secured on the rotatable sleeve 106' provided with similar sets of radial passages 116' communicating with passage 114', the sleeve 106' being rotatably journaled on a second fixed sleeve 136. The teeth of the gear 104' may also be provided on one side with radial slots 115 axially positioned between the sets of passages 114'.

The sleeve 136 is secured to the pump housing member 92 and the cover 94 by a flange 137 formed on one end of the sleeve and a threaded plug 138 secured to the other end thereof. A second threaded plug 139 seals the flanged end of the sleeve. The sleeve 136 is provided with peripheral chambers or slots 140 and 142 generally similar to the chambers 118 and 119, previously described, except that they are axially as well as angularly spaced. The slots 140 and 142 communicate through the sets of radial passages 116' and 114' of the sleeve 106' and the gear 104' with the pump chambers 146 and 144. A shiftable valve member 148 is included as a part of the pump and is slidably mounted within the sleeve 136 for movement between the threaded plugs 138 and 139, and this member is provided with a plurality of valve heads 150, 152 and 154. The valve head 152 selectively controls communication between radial ports 156 and 158 in the sleeve 136 and the interior chambers 160 and 164 of the sleeve 136, the ports 156 and 158 registering with the peripheral chambers or slots 142 and 140 in said sleeve. Chambers 160 and 164 are in constant communication with the main reservoir 22 by means of passages 162 and 166. The valve head 150 seals the chamber 160 and the valve head 154 seals the chamber 164. Liquid for shifting the valve member 148 is supplied to the interior of the sleeve 136 on the outer sides of the valve heads 150 and 154 by means of ports or passages 168 and 170 which are connected to the ports or passages 174 and 172 through which liquid passes to and from the chambers 178 and 176 of a cylinder 180, to and from the pump chamber 146 and 144. The cylinder 180 corresponds to cylinder 36 of Figure 4 and has mounted therein a translatable shiftable piston 182. The cylinder 160 and piston 182 of Figure 6 perform the same functions as do the cylinder 36 and piston 38 of Figure 4.

As the pump driving gear 102 rotates in a counterclockwise direction, as seen in Fig. 6, liquid is withdrawn from the cylinder chamber 178 on the piston rod side of the piston 182 through the port 174 into the pump chamber 146 and supplied under pressure from the pump chamber 144 to the cylinder chamber 176 through the port 172, causing piston 182 to move to the right as

seen in Fig. 6. The pressure of the liquid in the port 170 which is in communication with the exhaust pump chamber 144, being greater than the pressure of the liquid in the port 168 which is in communication with the inlet pump chamber 146, the valve member 148 is moved to the left to the position shown in Fig. 5. As the piston 182 moves to the right, there is less liquid available in the cylinder chamber 178 per unit of movement of the piston than is required for the cylinder chamber 176. This deficiency of liquid is compensated for by the drawing of the required liquid into the inlet pump chamber 146 from the main reservoir 22. This liquid is drawn from the reservoir through passageway 166, chamber 164, passageway 158 which is now open because the valve member 148 is in the position of Figure 5, slot 140 and passageways 116' and 114' into the inlet pump chamber 146.

When the pump driving gear 102 is rotated in the opposite direction to effect movement of the piston 182 to the left, as seen in Fig. 6, liquid is withdrawn from the cylinder chamber 176 into the pump chamber 144 through the port 172 and is supplied under pressure to the cylinder chamber 178 from the pump chamber 146 through the port 174. Pump chamber 146 now being on the exhaust or pressure side of the pump, pressure is transmitted through the passageway 166 to act on the valve head 150 and cause the shifting of valve member 148 to the right, away from the position shown in Fig. 5, opening the passageway 156 and closing the passageway 158 by the shifting of the valve head 152. As the actuator piston 182 now moves to the left, the volume of liquid displaced by the piston from the cylinder chamber 176 is greater than that required for the cylinder chamber 178 per unit of piston movement. Passageway 156 now being open, this excess liquid is by-passed from the pump chamber 144 through radial passageways 116' and 114', slot 142, passageway 156, chamber 160, and passageway 162 into the main liquid reservoir.

It will be seen that due to the shiftable valve member 148 the passageways 156 and 158 are closed when on the high pressure side of the pump and open when on the low pressure side thereof to compensate for liquid excess or deficiency. Compensation is made for the differences in volume on the two sides of the actuator piston 182 without any loss of pressure on the pressure side of the pump.

The slots or chambers 140 and 142 not only cooperate with passages 158 and 156 to compensate for liquid excess or deficiency, in the manner stated, but they also act to prevent crushing of the fluid in the manner previously described with reference to chambers 118 and 119 in Figures 1-4. The radial passageways 114' and 116' cooperate with the chambers to prevent crushing of the liquid at the base of the teeth of the gear 104', and the radial slots 115 in effect communicate with passages 114' and 116' to prevent crushing of the fluid at the base of the teeth in the gear 102. The chambers 140 and 142 remain operative to prevent fluid crushing even when the associated passageways 158 and 156 are closed.

Suitable means, forming no part of the present invention, may be provided for initiating and controlling the forward and reverse operation of the motor or motors 18.

In Figs. 8, 9 and 10 a valve actuating installation is set forth as illustrative of a further instance of use of the present invention. As

shown, the installation set forth in Fig. 8 may, for example, comprise a part of the piping system of a gasoline or oil refining installation. In systems of this type the various valves in the installation must be opened and closed quickly, positively, and efficiently, as may be effected by means of the pump structure of the present invention. Further, the arrangement is such that the valve actuating piston rod projects from the hydraulic actuator in but one direction, creating the problems of differential fluid delivery to and from the pump, as previously described.

Referring more specifically to Fig. 8, the piping system shown may comprise a main pipe line 500 and auxiliary pipe lines 502, 504 and 506 through which various treating agents may be introduced into the main pipe line or through which liquid or fluid therein may be withdrawn. Valves 508, 510, 512 and 514 are provided in the main pipe line to control the flow of fluid therethrough and to the various auxiliary pipes. These valves are provided with hydraulic actuating units 516, 518, 520 and 522, respectively.

Each of the valve structures and their associated hydraulic actuating units may be identical in construction. As shown in Figs. 9 and 10, each includes a valve rod 530, to the lower end of which the valve member of the unit is secured. The valve rod extends upwardly through the valve bonnet structure 532 which forms the support for the hydraulic actuating unit.

At its upper end the valve stem 530 is connected to the actuating piston rod 548 of the actuating unit, the valve stem also having connection with the actuating rod 556 of an electric motor control switch structure 558, forming no part of the present invention.

In addition to the piston rod 548, the actuator unit comprises a main cylinder casting 568 having two different size cylinder bores 568 and 570, the upper bore containing the piston 572 secured to the upper end of the piston rod 548, and the lower bore containing a floating piston 574; the latter having a head portion 576 extending upwardly for engagement with the upper piston.

Each actuator unit further includes an electric motor 578, Fig. 10, a pump 580, and a fluid reservoir 582. This pump structure may be of the type previously described in reference to Figs. 3 and 4, or of the type specifically described in reference to Figs. 5, 6 and 7. The main casting of the pump forms one wall of the oil reservoir 582, the other walls of which are formed by the housing 583. The pump is mechanically connected to the motor 578 by means of a coupling 590, as shown in Fig. 10.

The ports or passages 592 and 594 connect the inlet and outlet ports 596 and 598 of the pump to the upper end of the cylinder bore 568 and to the lower end of the cylinder bore 570, the ports or passages 592 and 594 being formed in the pump casting, and in the associated parts of the hydraulic actuator, eliminating the need for any outside piping. The fluid passage or port 600 extends through the main cylinder casting 568 from the upper end of the cylinder bore 568 to the lower cylinder 570. The enlarged central bore 602 of the piston head 576 provide a fluid passage about the piston rod 548, permitting the fluid to pass from the under side of the piston 574 to the under side of the piston 572.

Assuming the valve structure to be closed, as shown in Fig. 9, upon operation of the pump in a direction to effect an upward movement of the piston rod 548, the pump withdraws fluid, which

is preferably oil, from the cylinder bore 568 above the piston head 572 through the port 592 into the pump port 596 and forces fluid through the port 598 and the port 594 into the cylinder bore 570 below the piston 574. The power or floating piston 574 under the force of the fluid moves freely for a predetermined distance determined by the space 604 until the upper end of the head portion 576 strikes the lower wall of the piston 572. Thereupon the piston 572 is propelled upwardly to effect the opening of the valve, the fluid being supplied thereto through the passage 602. The piston 574 moves only a predetermined selected distance until stopped by the upper wall of the cylinder bore 570.

Upon operation of the pump in the opposite direction, to effect the closing of the valve, fluid will be withdrawn from the cylinder chamber 568 beneath the piston 572 and from the cylinder chamber 570 beneath the piston 574 through the port 594 to the pump port 598, and forced under pressure through the pump port 596 and the port 592 into the cylinder chamber 568 above the piston 572. Fluid is also forced into the cylinder chamber 570 above the piston 574 from the cylinder chamber 568 through the port 600. This operation forces both of the pistons 572 and 574 downwardly to effect the closing of the valve.

It will be seen that in this instance not only does the piston rod 548 project in a uni-directional manner from the hydraulic actuator, but two pistons of different size and movable at different times are provided, the pump being interconnected therewith in a closed circuit. The differential in oil delivery to and from the pump, under the various operating conditions, may be compensated by the means heretofore described either in reference to Figs. 3 and 4, or in reference to Figs. 5, 6 and 7.

It is obvious that various changes may be made in the specific embodiments set forth without departing from the spirit of the invention. The invention is accordingly not to be limited to the embodiments shown and described, but only as indicated in the following claims.

The invention is hereby claimed as follows:

1. A reversible pump for pumping fluid to and from a source of variable capacity, said pump comprising a casing, a plurality of cooperating and relatively rotating fluid pressure generating members therein, inlet and exhaust passageways in the casing communicating with said members, auxiliary passage means providing a fluid path communicating through the casing with the path of rotation of at least one of said members in the pressure zone thereof, a fluid reservoir communicating with said auxiliary passage means, and means subjecting said auxiliary passage means to variations in fluid pressure in the path of rotation of the member with which the passage means communicates whereby to modify the fluid volumes exhausted from and delivered to said source by said members.

2. A reversible pump as claimed in claim 1, wherein the casing includes a pump chamber in which the fluid pressure generating members are disposed and with which the inlet and exhaust passageways communicate, and wherein the pressure zone of said fluid pressure generating member is defined by surfaces including the periphery thereof and the wall of said chamber.

3. A reversible pump as claimed in claim 1, including valve means for controlling the passage of fluid through said auxiliary passage means.

4. A reversible pump as claimed in claim 3,

wherein the auxiliary passage means includes a pair of passages and the valve means is shiftable to selectively control the flow of fluid through said passages.

5. A reversible pump as claimed in claim 1, wherein the auxiliary passage means comprises a pair of passages on opposite sides of the casing and each communicating with the path of rotation of the periphery of a separate pressure generating member.

6. A reversible pump for pumping fluid to and from a source of variable capacity, said pump comprising a casing, a plurality of cooperating and relatively rotating fluid pressure generating members therein, inlet and exhaust passageways in said casing communicating with said members, a fixed sleeve mounted in said casing and on which one of said members is mounted, said sleeve having a valve chamber internally thereof, a pair of auxiliary passages including aperture means through said sleeve communicating through said valve chamber with the path of rotation of the periphery of at least one of said members, a fluid reservoir communicating with said auxiliary passages, a valve plunger mounted within said valve chamber and including valve means shiftable to selectively open one and close the other of said passages, and means effecting the shifting of said valve plunger and valve means in response to variations in fluid pressure in the inlet and 25 exhaust passageways to open one and close the other of said auxiliary passages and subject the one to variations in fluid pressure in the path of

10

rotation of the periphery of the communicant pressure generating member whereby to modify the fluid volumes exhausted from and delivered to said source by said members.

7. A reversible pump as claimed in claim 6, wherein one of said pressure generating members is provided with peripherally spaced ports successively communicating with said aperture means as the member rotates to afford communication between the aperture means and the pressure generating area of said members.

ERNEST J. SVENSON.
